WINDING MECHANISM FOR PAPER BOTTLES

Andrew Bodor, Newark, N. J., assignor to Reinforced Paper Bottle Corporation, New York, N. Y., a corporation of Delaware

Application March 9, 1933, Serial No. 660,087

6 Claims. (Cl. 93—79)

My invention relates to improvements in paper bottle making machines and refers to one of the particular mechanisms which comprise the complete machine whereby a paper bottle is completely made, and this particular invention relates to the winding mechanism whereby the body of the bottle is completely wound into bottle form.

My invention consists briefly of a divided shell housing carried at each end by arms pivotally connected to brackets connected to the bed plate of the machine, a mandrel extending into the shell-housing conforming to its interior shape and forming part of a turret and means for opening and closing the divided parts of the shell-housing in order to allow of the body of the bottle when formed, to be carried on its way by the rotation of the turret to the various other bottle forming operations, the parts of this particular winding mechanism being hereinafter more particularly explained.

Fig. 1 is a plan view of the winding mechanism showing the position of the blanks on the feed table preparatory to being fed into the winding mechanism and the body of the bottle as delivered, completely wound, therefrom.

Fig. 2 is an end elevation of the winding mechanism taken from the feed end of the machine, the machine mostly being broken away.

Fig. 3 is a vertical section of the winding mechanism taken on the line 3—3, Fig. 2.

Fig. 4 is a vertical section of the winding mechanism taken on the line 4—4, Fig. 2.

Fig. 5 is a side elevation showing the mechanism whereby the arms of the divided shell-housing are operated, the housing being shown closed.

Fig. 6 is a similar view to Fig. 5 showing the housing opened and showing the rotatable turret and a series of mandrels carried thereby.

Fig. 7 is a fragmentary end elevation of a portion of the divided shell-housing part of which being broken away.

In the drawings like characters of reference indicate corresponding parts in the different views.

1 is the feed table which has inwardly projecting side portions 2, and central portions 3, the inner edge of which is made to conform to the longitudinal form of the shell-housing against which it closely fits.

4 and 5 are the paper blanks from which the paper bottles are formed. The blank 5 extends underneath the edge of the blank 4 and such blank 4 has a strip of glue 4' imparted to it underneath the approximate width of which is indicated by 4² Fig. 1. The strip 4 has the glue imparted to it by a glueing device forming the

subject matter of an application filed concurrently herewith. The feeding of the arc-shaped blank also forms the subject matter of a concurrent application but it is sufficient to say that the inner arc shaped portion of the blank 5 is arranged so that it overlaps and is caused to adhere to the glued strip 4' as the blanks are being wound.

The rear portion of the blanks 4 and 5 are also glued to the extent of one half of them by a glueing attachment which is not further referred to on account of the same being the subject matter of a subsequent application.

8 is one of the mandrels of a turret forming part of the main machine and having the cylindrical portion 8' and the tapered portion 8². 9 is a gear on the mandrel 8 which engages with a gear pinion 10 on the spindle 11 carrying the rollers 12 (see Figs. 2 and 4).

13 is one portion of the shell-housing which is carried by the end arms 14, and 15 is the co-acting portion of the divided housing which is carried by the end arms 16. The end arms 14 and 16 are pivoted on a rod 17 held in a bracket 18 which is secured to the bed plate of the machine. 25 The divided housing 13, 15 abut at the top but at the lower portion opposite the feed table 1 are separated to provide an opening 19 which has the guiding lips 20 and 21 forming part of the housings 13 and 15 respectively and into proximity to which the feed table 1 extends.

The portion 13 of the divided housing is provided with a series of openings 22 on its upper portion, such openings having springs 23 in them designed to maintain a tension on the blanks 4 and 5 as they are being wound on the mandrel 8.

The shaft 11 is in two parts as indicated in dotted lines in Fig. 2 being connected together intermediate of its length by the universal joint 24. The shaft is made in two portions in order to provide for the taper of the body of the bottle.

Beneath the roller 12 is located a cradle 25 which is arc-shaped in cross section as indicated in Fig. 4 and longitudinally is made to conform to and fit the shape of the divided roller 12. 26 45 are rollers having broad V shaped peripheries and are carried on spindles 27 journaled to the yoke 28 adjustably secured to the cradle 25 by the set screw 29. The rollers 26 maintain a pressure upon the roller 12 so as to bring it to bear against the mandrel 8 and thereby enable the blanks to be fed between the mandrel 8 and the housing 13, 15 after the front edge of the blanks have passed through the opening 19 and thus enable the blanks to be wound around the man- 55

drel after having glue imparted to them and delivered into the body form shown in Fig. 1.

In order to deliver the mandrel with the paper bottle body wound upon it to the next succeeding operation and at the same time to provide for the reception of a new mandrel, it is necessary to open the divided shell-housing and this I do by the following mechanism.

30 is a counter shaft supported in suitable bearings in the frame of the machine and 31 is a cam secured to the shaft 30. 32 is a link pivotally connected to a pin 33 on the portion 13 of the divided shell-housing at one end and at the opposite end to an arm 34 by a pin 35. The arm 15 34 is secured on the stud 36 supported in suitable bearings in the bed plate of the machine. 37 is a link pivotally connected to the pin 38 on the portion 15 of the divided shell-housing.

The link 37 is connected to a bell crank arm 39 secured to the stud shaft 36. 40 is a bell crank arm secured to the shaft 36 and is connected to a rod 41 which coacts with the cam 31 through the medium of a roller 42.

It will now be seen on reference to Figs. 5 and 25 6 that the divided portions 13 and 15 are both opened and closed through the medium of the cam 31 and the connecting rods and arms hereinbefore described.

In order to hold the paper taut on the mandrel as it is being wound I provide, in addition to the rollers 26 hereinbefore described, the rollers 30 43 secured on suitable studs 44 (see Figs. 2 and 4).

In order to hold the roller 12 resiliently against the mandrel 8, I provide on each arm 16 at the 35 end of the cradle 25 a depending boss 45 which is provided with a recess 46 into which the ends 25' of the cradle 25 fit, being supported therein by spiral springs 47 fitting in a recess 47' and resting on a cross bar 48 held in place by set 40 screws 49 extending into the bosses 45. It will thus be seen that the roller 12 will be resiliently held against the roller 8 in order to accommodate the increased thickness of the paper when being wound on the mandrel.

45 It will be seen from this description that I have provided a very effective winding mechanism whereby the connected rectangular and arc-shaped blanks may be wound into bottle form.

What I claim as my invention is:

50 1. The combination with a mandrel comprising a cylindrical straight portion and a frusto-conical portion, of a shell having its interior walls spaced from the mandrel a distance equal to the thickness of the blank and corresponding in shape to the shape of the straight and tapered portion 55 of the mandrel and means for simultaneously winding a blank portion around each straight and tapered portion of the mandrel with their adjacent edges in lapped position to form a bottle body.

60 2. The combination with a rotating turret and a series of mandrels mounted thereon to travel in a circular path, of a divided shell housing surrounding the mandrel the lower shell portion having a peripheral entrance mouth through which paper blanks are fed to engage the revolving mandrel, a pivot, a pair of arms swung thereon and on which the shell portions are respectively mounted to swing out of and into the path of the 65 mandrel to enclose the same.

3. The combination with a mandrel comprising a cylindrical straight portion and a frusto-conical portion formed integral, of a shell having its walls spaced from the mandrel a distance equal to the thickness of the paper blank, a feed mouth in the shell for the passage of a blank around each portion of the mandrel, a cradle carried by and extending longitudinally beneath the shell and parallel thereto and having a longitudinal slot in the bottom thereof, a divided 10 shaft journalled at its ends in the end walls of the shell a universal joint connection between the inner ends of the shaft members, a roller mounted on each shaft member to engage the straight and tapered portions of the mandrel, 15 and a broad V shaped roller engaging the peripheries of the aforesaid rollers at their adjacent ends and spring pressed thereagainst to retain the rollers in contact with the mandrel.

4. The combination with a suitably rotated 20 mandrel comprising a cylindrical straight portion and a frusto-conical portion, of a shell having its interior periphery spaced from the straight and frusto-conical portions of the mandrel to permit the winding of a bottle blank around the mandrel 25 between the mandrel and shell and having a longitudinal slot and a blank feeding slot therein, roller members contacting through the longitudinal slot with the straight and inclined peripheries of the mandrel, and means for driving the roller 30 members in unison from the mandrel.

5. The combination with a suitably rotated mandrel comprising a cylindrical straight portion and a frusto-conical portion, of a shell having its interior periphery spaced from the straight 35 and frusto-conical portions of the mandrel to permit the winding of a bottle blank around the mandrel between the mandrel and shell and having a longitudinal slot and a blank feeding slot therein, horizontal and inclined roller members 40 contacting through the longitudinal slot respectively with the straight and inclined peripheries of the mandrel, means for driving the roller members in unison from the mandrel, and means for resiliently holding the inclined roller member 45 in contact with the inclined periphery portion of the mandrel and the adjacent inner end of the roller member in contact with the straight periphery of the mandrel.

6. The combination with a suitably rotated 50 mandrel comprising a cylindrical straight portion and a frusto-conical portion, of a shell having its interior periphery spaced from the straight and frusto-conical portions of the mandrel to permit the winding of a bottle blank around the 55 mandrel between the mandrel and shell and having a longitudinal slot and a blank feeding slot therein, roller members contacting through the longitudinal slot with the straight and inclined peripheries of the mandrel, means for driving the roller members in unison from the mandrel, a cradle extending parallel to the straight and inclined peripheral portions of the shell and resiliently pressed upward, roller members revolvably mounted in the cradle to contact with straight 60 and inclined peripheral portions of the mandrel, and a V-roller journalled in the cradle and spring held upward against the peripheries of the adjacent ends of the roller members.

ANDREW BODOR. 70
